INDICATING CHAPLET

Norris P. Tilleman, Green Bay, Wis.

Application April 26, 1950, Serial No. 158,222

2 Claims. (Cl. 35—23)

1

My invention relates to chaplets such as used in devotional exercises, and particularly to new and useful improvements in indicating chaplets.

A chaplet is a string of devotional beads used to assist in counting a particular series of prayers. It comprises five decades of beads, or a third of a regulation rosary which has 15 decades. It is an abbreviated rosary.

An indicating chaplet is a chaplet especially adapted for instruction through means of indicia on the large beads thereof.

The chaplet as is commonly known comprises fifty beads arranged in series of ten, and each series is separated by a single larger bead which is spaced from the series beads a greater distance than is each of such series to its companion. The described arrangement is of endless chain form, and at an appropriate point there is connected to the chain a short length which terminates in a crucifix or cross, there being a large bead next adjacent the crucifix, and spaced therefrom and in close series arrangement are three smaller beads with an intervening space and a fourth large bead which is itself spaced from the endless chain. Upon the crucifix and these five beads, prayers introductory to the rosary are said.

The rosary when practiced, consists of two distinct modes of prayers, used together in one exercise, or in other words, it is a combination of mental prayer or meditation with vocal prayer. The meditation or mental prayer is made by the consideration of the most memorable or touching events called "mysteries" in the life, passion, and victory of Jesus. The vocal prayer consists of the recitation of the Ave Maria prayer on the small beads, and the recitation of the Pater Noster prayer on the large beads, concluded by a Gloria Pateri prayer. A different mystery for meditation is assigned to each of the decades.

To make a chaplet especially adapted for instruction, each pater noster or large bead is provided with an indicia or inscription denoting each mystery in its proper order, so that the user can readily tell by a glance at the beads the proper mystery to be meditated upon during the next decade of prayers.

It is an object of my invention to provide an indicating chaplet with cylindrical indicating beads, rollable between the finger tips to facilitate the inspection of indicia or printing thereon.

It is another object of my invention to provide an indicating chaplet with indicating beads serially numbered so that the user may proceed in an orderly way around the rosary chain.

2

It is a further object of my invention to provide an indicating chaplet with indicating beads bearing indicia, or printing, colored according to rubric or prescribed form.

It is a still further object of my invention to provide an indicating chaplet with indicating beads, each bead bearing indicia or printing of a plurality of colors, each color being reserved for a particular series of meditations, thereby to more readily identify a particular series as the user proceeds around the rosary chain.

It is yet a further object of my invention to provide indicating beads, bearing indicia, the backgrounds of which are colored according to rubric, thereby to more readily identify a particular series of meditations as the user proceeds around the rosary chain.

It is still another object of my invention to provide an indicating chaplet with indicating beads, each bead comprising a transparent cylinder through which is visible indicia therein.

It is yet another object of my invention to provide chaplet indicating beads having luminescent indicia thereon for visibility in the darkness and in dimly lighted churches.

Other objects and many of the attendant advantages of this invention will be readily appreciated as the same becomes better understood by reference to the following detailed description 30 when considered in connection with the accompanying drawings in which like reference numerals designate like parts throughout the figures thereof and wherein:

Fig. 1 shows a chaplet embodying my indicating beads;

Fig. 2 is an enlarged exploded view showing the details of one construction of my indicating beads;

Fig. 3 shows a double-eye rod-link that is disposed through the indicating beads for linking the assembled beads with the adjacent decade beads;

Fig. 4 is an enlarged development of the cylindrical indicia sheet of Fig. 2, specific to the date bead 18, Fig. 1, and which can be rolled for insertion into the transparent plastic cylinder which forms the casing of the indicating bead;

Figs. 5, 6, 7, 8 and 9 are enlarged developments 50 of the cylindrical indicia sheets showing mystery indicia thereon, specific to certain beads, and showing the indicia colored according to Catholic Church rubric;

Fig. 10 is a development of a modified rolled 55 sheet showing indicia background being colored

in lieu of coloring the indicia itself, and the indicia being coated with a luminescent material;

Fig. 11 is an exploded view modification of the bead shown in Fig. 2, showing principally another end cap arrangement;

Fig. 12 shows another modification of the bead casing principally in that the indicia are formed on the inner periphery of the bead casing;

Fig. 13 shows a further modification of the bead casing principally in that the indicia are formed on the outer periphery of the bead casing; and

Fig. 14 shows yet another modification of the bead casing principally in that the casing is hexagonal in form;

Fig. 15 shows still another modification illustrating solid cylindrical bead.

Referring now to the drawings, wherein like reference characters designate like or corresponding parts throughout the several views, there is shown in Fig. 1, which illustrates a preferred embodiment, a chaplet comprised of a string of linked beads with a crucifix attached. On this string is included five decades of small beads. Each decade is preceded by a pater noster or large bead, followed by ten ave marias or smaller beads. At an appropriate point there is connected to the chain a short length which terminates in a crucifix. This short length contains two large beads and three smaller beads therebetween for introductory prayers.

All the large or indicating beads comprise a transparent plastic tubular casing 11, Fig. 2, having snugly inserted therein a tubular sheet 12 bearing indicia or printing thereon (to be described hereafter) visible through said transparent tube 11; and within said tubular sheet element 12 is snugly inserted a tubular element 13. Said tubular elements 11, 12 and 13 are all of the same length and bound together by end cap closures 14, centrally apertured, and have 40 tubular portions 15 receivable by and frictionally engageable with the inner periphery of said tubular elements 13, and outstanding flanges 16 that are abuttingly engageable with the ends of said tubular elements, when assembled. The sheet 12 can be of paper, foil, metal, or any other suitable material.

A double-eye rod-link 17, Fig. 3, is disposed through said tubular element 13 and the end caps 14 to enable the assembled large indicating beads to be linked with the adjacent decade beads. The assembled bead is rotatable about the link as an axis, as the assembled bead is rolled between the finger tips. The cylindrical casing lends itself to be conveniently rolled between the finger tips.

Beads of this construction are embodied in the chaplet of Fig. 1, and appear therein as beads 18, 21, 23, 25, 27 and 29.

According to custom, some of the mysteries hereinbefore referred to are used for reflection on certain days of the week and within penitential seasons, and others upon other days and other seasons. In accordance therewith, within the large bead 18, next adjacent the crucifix 19, a rolled sheet 20, Fig. 4, indicates that the joyful mysteries, indicated by the capital letter J, are to be reflected upon on Mondays, Thursdays, and the Sundays in Advent; the sorrowful mysteries indicated by the capital letter S, are to be reflected on Tuesdays, Fridays, and the Sundays in Lent; and the glorious mysteries indicated by the capital letter G, are to be reflected upon on Wednesdays, Saturdays, and all other Sundays. This cylindrical bead 18 is called the date indi-

cating bead. The remaining large indicating beads are known as the mystery indicating beads.

Within the mystery indicating bead 21, a rolled sheet 22, Fig. 5, indicates, in abbreviation, the first joyful mystery (the annunciation), the first sorrowful mystery (the agony in the garden), and the first glorious mystery (the resurrection of our Lord).

Within the mystery indicating bead 23, a rolled sheet 24, Fig. 6, indicates, in abbreviation, the second joyful mystery (the visitation), the second sorrowful mystery (the scourging), and the second glorious mystery (the ascension).

Within the mystery indicating bead 25, a rolled sheet 26, Fig. 7, indicates, in abbreviation, the third joyful mystery (the nativity or birth of Christ), the third sorrowful mystery (the crowning with thorns), and the third glorious mystery (the descent of the Holy Ghost).

Within the mystery indicating bead 27, a rolled sheet 28, Fig. 8, indicates, in abbreviation, the fourth joyful mystery (the presentation in the temple), the fourth sorrowful mystery (the carrying of the cross), and the fourth glorious mystery (the assumption of Mary into heaven).

Within the mystery indicating bead 29, a rolled sheet 30, Fig. 9, indicates, in abbreviation, the fifth joyful mystery (the finding in the temple with the doctors), the fifth sorrowful mystery (the crucifixion), and the fifth glorious mystery (the coronation of Mary queen of heaven).

It is to be noted that the joyful, sorrowful and glorious mysteries are all serially numbered by the numerals 1, 2, 3, 4 and 5 around the rosary to indicate the order of contemplation and the direction of procedure.

It is to be further noted that the joyful, sorrowful and glorious mystery indicia are colored according to Catholic Church rubric or prescribed form. That is, the joyful mystery indicia are to be colored green or red, green being preferred and indicated on the figures of the drawing; the sorrowful mystery indicia are colored purple; and the glorious mystery indicia are to be colored white or golden yellow, white being preferred and indicated.

Also the date bead 18, Fig. 4, has its rolled sheet 20 indicia correspondingly colored, that is, the dates on which the joyful mysteries are to be reflected upon are to be colored green or red, green being preferred and indicated; the sorrowful mystery date indications are colored purple; and the glorious mystery indications are to be colored white or golden yellow, white being preferred and indicated.

It is obvious that in lieu of the indicia being colored, the back grounds for all the indicia can be appropriately colored as shown in Fig. 10. In this disclosure, sheet 32, which could be any of the bead sheets, is provided with luminescent indicia 33, the backgrounds therefor are colored in accordance with Catholic Church rubric. That is, the background for the joyful mystery being green or red, green being preferred and indicated as at 34; the background for the sorrowful mystery being purple as indicated at 35; and the background for the glorious mystery being white or golden yellow, white being preferred and indicated as at 36.

The bead modification of Fig. 11 differs from the bead structure of Fig. 2 only in the end cap arrangement. In this modified structure the end cap closures 37 have their tubular portions 38 receivable by and frictionally engageable with the inner periphery 39 of the casing element 41.

Said cap closures are additionally frictionally engageable with the outer periphery of the cylindrical core element.

The bead casing modification of Fig. 12 shows a transparent cylindrical casing 42 having indicia 43 formed on the inner periphery 44 of the casing.

The bead casing modification of Fig. 13 shows a cylindrical casing 45 having indicia 46 formed on the outer periphery 47 of the casing. The 10 end caps 51 thereof engage with the outer periphery of the casing 45.

It is obvious that the cap closure 51 of Fig. 13 can be substituted for the cap closures 14 of Fig. 2 to provide a composite subsidiary modification. In this modification the cap closures 51 are receivable by and frictionally engageable with the outer periphery of casing 11.

The bead casing modification of Fig. 14 shows a transparent hexagonal casing 48 having indicia 49 formed on the outer faces of said casing. The 20 end caps 52 thereof engage with the inner periphery of the casing 48.

The bead modification of Fig. 15 shows a rodular bead 53 having a fine bore therethrough to receive a link 54 and be rotatable thereon. The 25 indicia 55 is formed in the outer periphery of said bead 53.

The characteristic features of this invention are chaplet indicating beads that are cylindrical in shape whereby to be more easily rollable between the finger tips to facilitate the inspection of indicia thereon; that are serially numbered so that the user may proceed in an orderly way around the rosary chain; that have indicia colored according to Catholic Church rubric and whereby to more readily identify each series of indicia as the user proceeds around the rosary chain; that is transparent and through which indicia therein is visible thereby protecting the indicia from external wear and damage; and that has luminescent indicia for visibility in the darkness.

Obviously many modifications and variations of the present invention are possible in the light of the above teachings. It is therefore to be understood, that within the scope of the appended claims, the invention may be practiced otherwise than as specifically described.

What is claimed and desired to be protected by Letters Patent of the United States is:

1. A chaplet including Pater Noster beads and a crucifix, said Pater Noster beads comprising a transparent tubular casing, a sheet in each casing fitting against the inner periphery of said casing, and a tubular element fitting against the inner periphery of said sheet; apertured end caps for said beads, having tubular projections engaging with the outer periphery of said element; and connecting means disposed through said apertures and through said tubular element, and adapted for connection into said chaplet; and said sheets having indicia on the outer periphery thereof.

2. A chaplet including Pater Noster beads and a crucifix, said Pater Noster beads comprising a transparent tubular casing, a sheet in each casing fitting against the inner periphery of said casing, and a tubular element fitting against the inner periphery of said sheet; apertured end caps for said beads, having tubular projections engaging with the inner periphery of said casing; and connecting means disposed through said apertures and through said tubular element, and adapted for connection into said chaplet; and said sheets having indicia on the outer periphery thereof.
